1

This invention relates to a method of transmitting telegraphic signals and also to transmitting and receiving devices arranged for the transmission and reception respectively of signals emitted by this method.

According to the invention, the mean energy required for the transmission is materially reduced by transmitting one or more pulses of substantially constant length of time at the beginning and in some cases at the end of each signal to be transmitted, either the pulses at the beginning of several signals or the pulses at the end and the beginning of the same signal having a differing time nature.

A further advantage of the method according to the invention consists in that the signal hiss ratio occurring in the receiver can be raised considerably over the signal hiss ratio obtainable in the usual transmission of telegraphic signals, the mean transmission energy being otherwise the same.

In order that the invention may be clearly understood and readily carried into effect it will now be described more fully with reference to the accompanying drawing.

The figures of the drawing are as follows:

Fig. 1 is a pattern of the telegraph signals to be transmitted.

Fig. 2 is a schematic diagram of a preferred embodiment of a transmitter for emitting pulses of the type shown in line b of Fig. 1.

Fig. 3 is a pattern illustrating various pulses generated in the transmitter of Fig. 1.

Fig. 4 is a schematic diagram of another preferred embodiment of a transmitter.

Fig. 5 is a schematic diagram of a receiver for the reception of pulses of the type shown in line d of Fig. 1, and

Fig. 6 is a schematic diagram of a pulse generator for use in connection with a receiver of the type shown in Fig. 5.

Figure 1 shows a telegraphic signal to be transmitted made up of a dash, a dot and a dash. The energy required for the transmission of the signal is proportional to the cross-hatched surface areas. For enabling the transmission of this energy a transmitter of definite power is required and this power must be such that the mean energy to be transmitted per time unit, or in other words the contents of the cross-hatched surfaces divided by the time T, can be coped with by the transmitter without overloading.

According to the invention, the telegraphic signals as shown in Figure 1a are transmitted by means of pulses of constant length of time, for

2

example of the nature shown in Figure 1b, 1c or 1d. In the case of the pulse nature shown in Figure 1b two short successive pulses are emitted at the beginning of each signal, whereas the end of each signal is denoted by a single pulse. In the case of the pulse nature shown in Figure 1c the beginning of each dash is represented by two pulses, the beginning of each dot and the end of both dashes and dots by a single pulse. The pulse nature shown in Figure 1d essentially corresponds with the nature shown in Figure 1c, the difference being that the pulses at the end of the telegraphic signals are emitted.

As before, the energy required for the transmission of pulses of the nature shown in the Figures 1b, 1c and 1d is decided by the surface area of the pulses. This energy is materially lower than the energy required for the transmission of the signals shown in Figure 1a. The same remark applies to the mean energy. The use of a transmitter of identical power therefore permits of the pulses shown in Figures 1b, 1c and 1d being emitted with considerably larger amplitudes and with greater steepness. This ensures a more favorable signal hiss ratio on the receiver side than in the case of transmitting the signals shown in Figure 1a, particularly if receivers sensitive to the flank steepness are used.

Figure 2 shows a transmitter device for emitting pulses of the nature shown in Figure 1b by wireless telegraphy. This transmitting device comprises a key 1, a device 2 for the conversion of telegraphic signals into pulses of the nature shown in Figure 1b, an amplifier 3 and a transmitter 4, in which a carrier wave is so modulated by the amplified pulses that carrier wave pulses are obtained, and in addition an aerial 5 by which the high-frequency oscillations are emitted.

At the beginning of a dash to be transmitted 40 the key 1 is moved to the left with the result that a condenser 6 becomes charged across a resistance 7 until the starting-up voltage of a grid-controlled gaseous discharge tube 8 is reached. At this moment the condenser 6 is suddenly discharged across the tube 8 with the result that a pulse-like voltage as represented in Figure 3 by the impulse 10 is set up across a resistance 9 in the cathode lead of the tube 8. Concurrently with the charging of the condenser 6 a condenser 11 becomes charged across a resistance 12. Due to the fact that the time constant of the charging circuit of the condenser 11 exceeds that of the charging circuit of the condenser 6, the starting-up voltage of the grid-controlled gaseous discharge tube 13 is reached slightly later than the

starting-up voltage of the tube 8. The starting-up of the tube 13 brings about a sudden discharge of the condenser 11 with the result that as before a pulse is set up across the resistance 9 said pulse being designated 14 in Figure 3 and occurring slightly later than the pulse 10.

At the end of the dash the key is moved to the right with the result that a condenser 15 becomes charged via a resistance 16 and, as the starting-up voltage of a grid-controlled gaseous discharge tube 16' is reached, gets discharged across this tube and sets up a pulse across the output resistance 9. This pulse is designated 17 in Figure 3.

At the beginning of the next signal two pulses 18 and 19 are set up in succession in an identical manner, whereas at the end of the signal a single pulse 20 is obtained.

The pulses obtained in succession across the resistance 9 are caused after amplification by an amplifier 3 in the transmitter 4 to modulate a carrier wave.

In the embodiment described, the grid circuits of the tubes 8, 13 and 16 include a common source of bias. If the bias voltages of the tubes 8, 13 and 16 are made singly variable the starting-up voltages can be so adjusted that the pulses generated by the tubes have an identical absolute height.

The device described also permits of setting up pulses of the nature shown in Figure 1d. In this case it is, however, necessary for the key 1 to be arranged so as to be moved into the lefthand position for setting up dashes, into the righthand position for setting up dots and to occupy an intermediate position of equilibrium in the intervals between the signals.

It is not essential that the tubes 8, 13 and 16 should be constituted by grid-controlled gaseous discharge tubes. It is directly possible to use standard neon tubes in the circuit described but in this case the starting-up voltage is no longer adjustable. In addition, the value of the voltage pulse across the output resistance is decided approximately by the difference between the starting-up and the operating voltages of the tubes. In this case, the amplitude of the voltage pulses set up is therefor generally smaller and amplification of the pulses before they are fed to the transmitter will be necessary.

In practice it has been found that in the use of neon tubes a common output resistance 9 in the cathode lead of the tubes does not involve any difficulty. In the use of grid-controlled gaseous discharge tubes it is desirable to employ the circuit arrangement shown in Figure 4. In this case, relative influencing of the tubes 8, 13 and 16 is avoided by including a separate resistance 21, 22 and 23 respectively in the cathode lead of each of the tubes and the feeding the voltages set up across these resistances via decoupling resistances 24, 25 and 26 respectively to a common output resistance 27.

A device for the reception of pulses of the nature shown in Figure 1a is shown in Figure 5, the oscillations received in the aerial 108 being fed to a receiver 101 which is arranged in the usual manner and in which after detection pulses of the nature shown in Figure 1b are set up. These pulses are fed, in some cases via a transfer device 102, later to be more fully described, to a device 103 which serves for the conversion of pulses into telegraphic signals. The telegraphic signals set up in the output circuit of the device 103 are fed to a reproduction device 104.

The device 103 comprises two discharge tubes 105 and 106, the anode circuit of one tube being connected to the grid circuit of the other tube, as in the case of the well-known kaliotron circuit arrangement which, as is well-known, has two positions of equilibrium in which either the tube 105 allows the passage of current and the tube 106 is blocked or conversely.

In the off position the tube 106 allows current to pass and the tube 105 is disrupted. If the pulses received are then fed to the grid of the tube 106, as shown in the figure, and this is effected in such manner that the grid of the tube becomes more positive, the circuit continues occupying the said position of equilibrium. In order to ensure that on reception of two associated pulses at the beginning of each signal the circuit passes to the other position of equilibrium, a tube 107 is connected in parallel with the tube 105 and has the received pulses fed to it via a resistance 108. In addition, a condenser 110 shunted by a very high resistance 109 is interconnected between the grid and the cathode of the tube 107. In the off position, the tube 107 is disrupted by means of a source of bias 111. The time constant of the integrating network formed by the elements 108, 109 and 110 is chosen to be such that only after reception of two pulses in quick succession the voltage set up by the pulses across the condenser 110 has increased to such an extent that the negative bias of the tube 107 is balanced at least in part and the tube 107 is rendered conductive. As soon as anode current passes in the tube 107 a voltage drop is set up across a resistance 112, which is included in the grid circuit of the tube 106 and puts this tube out of operation, the tube 105 becoming thus conductive.

At the beginning of the second of two associated pulses a voltage drop is consequently set up across a resistance 113 in the cathode lead of the tube 105, said voltage drop subsisting until under the influence of the single pulse received at the end of the signal the tube 106 is again rendered conductive so that the tube 105 is disrupted. Thus, telegraphic signals are consequently received across the resistance 113 and are fed to the reproduction device 104.

In order to secure a stable operation of the device 103 it is desirable that the pulses fed to the latter should have identical amplitude at all times. For this purpose, provision is made for a device 102 which is constituted for example by a limiter. Preferably, however, it is constituted by a device for generating pulses which is normally disrupted and is governed by the pulses received.

One form of construction of such a device is shown in Figure 6. The device concerned is constituted by a relaxation generator comprising a condenser 114 which can be charged across a resistance 115 and can be discharged across a relay tube 116, each time the grid of the tube 116 has fed to it a received pulse. At each discharge of the condenser a pulse-like voltage can be obtained via a resistance 117 included in the cathode lead.

In order to prevent disturbances which are set up between the pulses and whose amplitude is lower than that of the pulses from bringing about a discharge of the condenser 114 the device 102 or a device preceding it is preferably given a threshold sensitiveness, for example by feeding a negative bias received from a source of voltage 118 to the grid of the tube 116.

What we claim is:

1. A method of communicating by continuous

wave radio telegraphy signals of the mark-space type, comprising the steps of converting the mark signals into pulse signals of substantially constant duration and spaced in time corresponding to the duration of said mark signals, the pulse signals corresponding to the initiation of said mark signals being different in number from those corresponding to the termination thereof, transmitting said pulse signals through space, receiving said signals, and converting said pulse signals back to said mark signals thereby reproducing said telegraphy signals.

2. A method of communicating by continuous wave radio telegraphy signals of the mark-space type, comprising the steps of converting the mark signals into pulse signals comprising a pair of pulses corresponding to the initiation of said mark signals and a single pulse corresponding to the termination of said mark signals, transmitting said pulse signals through space, receiving said pulse signals, and converting said received pulse signals back to said mark signals thereby reproducing said telegraphy signals.

3. A method of communicating by continuous wave radio telegraphy signals of the dot-space-dash type, comprising the steps of converting the dot signals into pulse signals comprising a single pulse corresponding to the initiation and termination of said dot signals and converting the dash signals into pulse signals comprising a pair of pulses corresponding to the initiation of said dash signal and a single pulse corresponding to the termination of said dash signal, transmitting said pulse signals through space, receiving said pulse signals, and converting said received pulse signals back to said dot-space-dash signals thereby reproducing said telegraphy signals.

4. A method of communicating by continuous wave radio telegraphy signals of the dot-and-dash type, comprising the steps of converting the dot signals into pulse signals comprising a single pulse corresponding to the initiation of said dot signals and converting the dash signals into pulse signals comprising a pair of pulses corresponding to the initiation of said dash signals, transmitting said pulse signals through space, receiving said pulse signals, and converting said received pulse signals back to said dot-and-dash signals thereby reproducing said telegraphy signals.

5. Apparatus for communicating by means of continuous wave radio telegraphy signals of the mark-space type, comprising a gaseous discharge tube device to convert the mark signals into pulse signals of substantially constant duration and spaced in time corresponding to the duration of said mark signals, the pulse signals corresponding to the initiation of said mark signals being different in number from those corresponding to the termination thereof, means to transmit said pulse signals through space, means to receive said transmitted pulse signals, and a second discharge tube device to convert said pulse signals back to said mark signals thereby to reproduce said telegraphy signals.

6. Apparatus for communicating by means of continuous wave radio telegraphy signals of the mark-space type, comprising a gaseous discharge tube device to convert the mark signals into pulse signals comprising a pair of pulses corresponding to the initiation of the mark signals and a single pulse corresponding to the termination of said mark signals, means to transmit said pulse signals through space, means to receive said transmitted pulse signals, and a second discharge tube

device to convert said pulse signals back to said mark signals thereby to reproduce said telegraphy signals.

7. Apparatus for communicating by means of continuous wave radio telegraphy signals of the dot-and-dash type, comprising a gaseous discharge tube device to convert the dot signals into pulse signals comprising a single pulse and to convert the dash signals into pulse signals comprising a pair of pulses, means to transmit said pulse signals through space, means to receive said transmitted pulse signals, and a second discharge tube device to convert said pulse signals back to said mark signals thereby to reproduce said telegraphy signals.

8. Apparatus for communicating by means of continuous wave radio telegraphy signals of the dot-and-dash type, comprising a gaseous discharge tube device to convert the dot signals into pulse signals comprising single pulses corresponding to the initiation and termination of said dot signals and to convert the dash signals into pulse signals comprising a pair of pulses corresponding to the initiation of said dash signals and a single pulse corresponding to the termination thereof, means to transmit said pulse signals through space, means to receive said transmitted pulse signals, and a second discharge tube device to convert said pulse signals back to said mark signals thereby to reproduce said telegraphy signals.

9. Apparatus for keying a continuous wave transmitter for radio telegraphy transmission of the mark-space type wherein the initiation and termination of each mark signals is represented by a different number of pulses of substantially constant duration, said duration being short in comparison to the duration of said mark signal, comprising a plurality of capacitors, each of said capacitors having a charging circuit and a discharging circuit, the discharging circuit of at least one of said plurality of capacitors having a time constant different from the remainder of said capacitors, means responsive to the initiation of said mark signal simultaneously to charge a given number of said plurality of capacitors, means to discharge said given number of said plurality of capacitors across the discharging circuit thereof, means responsive to the termination of said mark signal to charge a different number of capacitors, means to discharge said different number of capacitors across the discharging circuit thereof, and means to connect the discharging circuits of said capacitors to said transmitter.

10. Apparatus for keying a continuous wave transmitter for radio telegraphy transmission of the mark-space type wherein the initiation and termination of each mark signal is represented respectively by a pair of pulses and a single pulse of substantially constant duration, comprising a first, a second and a third capacitor, each of said capacitors having a charging circuit and a discharging circuit, the discharging circuits of said first and said second capacitors having different time constants, means responsive to the initiation of said mark signal simultaneously to charge said first and said second capacitors, means to discharge said capacitors in succession across the discharging circuits thereof, means responsive to the termination of said mark signal to close the charging circuit of said third capacitor, means to discharge said third capacitor across the discharging circuit thereof,

and means to connect the discharging circuits of said capacitors to said transmitter.

11. Apparatus for keying a continuous wave transmitter for radio telegraphy transmission of the dot-and-dash type wherein the initiation and termination of each dot signal is represented respectively by a single pulse and the initiation and termination of each dash signal is represented by a pair of pulses and a single pulse of substantially constant duration, comprising a first, a second and a third capacitor, each of said capacitors having a charging circuit and a discharging circuit, the discharging circuits of said first and said second capacitors having different time constants, means responsive to the initiation of said dash signal to close the charging circuits of said first and said second capacitors simultaneously to charge said first and said second capacitors, means to discharge said capacitors in succession across the discharging circuits thereof, means responsive to the termination of said dash signal to close the charging circuit of said third capacitor, means responsive to the initiation and termination of said dot signal to charge said third capacitor, means to discharge said third capacitor across the discharging circuit thereof, and means to connect the discharging circuits of said capacitors to said transmitter.

12. Apparatus for keying a continuous wave transmitter for radio telegraphy transmission of the dot-and-dash type wherein the initiation of each dot signal is represented respectively by a single pulse and the initiation of each dash signal is represented by a pair of pulses of substantially constant duration, comprising a first, a second and a third capacitor, each of said capacitors having a charging circuit and a discharging circuit, the discharging circuits of said first and said second capacitors having different time constants, means responsive to the initiation of said dash signal to close the charging circuits of said first and said second capacitors simultaneously to charge said first and said second capacitors, means to discharge said capacitors in succession across the discharging circuits thereof, means responsive to the initiation of said dot signal to close the charging circuit of said third capacitor, means to discharge said third capacitor across the discharging circuit thereof, and means to connect the discharging circuits of said capacitors to said transmitter.

13. Apparatus for keying a continuous wave transmitter for radio telegraphy transmission of the mark-space type wherein the initiation and termination of each mark signal is represented respectively by a pair of pulses and a single pulse of substantially constant duration, comprising a first, a second, and a third capacitor, each of said capacitors having a charging circuit and a discharging circuit comprising a gaseous discharge tube and a resistor, the discharging circuits of said first and said second capacitors having different time constants, means responsive to the initiation of said mark signal to close the charging circuits of said first and said second capacitors simultaneously to charge said first and said second capacitors, means comprising the gaseous discharge tubes of the respective discharging circuits to discharge said capacitors in succession across said resistor, means responsive to the termination of said mark signal to close the charging circuit of said third capacitor to charge said capacitor, means comprising the gaseous discharge tube of the respective discharging circuit to dis-

charge said third capacitor across said resistor, and means to connect the discharging circuits of said capacitors to said transmitter.

14. Apparatus for keying a continuous wave transmitter for radio telegraphy transmission of the mark-space type wherein the initiation and termination of each mark signal is represented respectively by a pair of pulses and a single pulse of substantially constant duration, comprising a first, a second and a third capacitor, each of said capacitors having a charging circuit and a discharging circuit comprising a grid-controlled gaseous discharge tube and a discharging resistor, the discharging circuits of said first and said second capacitors having different time constants, means responsive to the initiation of said mark signal to close the charging circuits of said first and said second capacitors simultaneously to charge said first and said second capacitors, means comprising the respective grid-controlled gaseous discharge tube of said discharging circuits to discharge said first and said second capacitors in succession across the discharging resistors of the respective discharging circuits, means responsive to the termination of said mark signal to close the charging circuit of said third capacitor to charge said third capacitor, means comprising the respective grid-controlled gaseous discharge tube to discharge said third capacitor across the discharging resistor of the respective discharge circuit, and means to connect the discharging circuits of said capacitors to said transmitter.

15. Apparatus for keying a continuous wave transmitter for radio telegraphy transmission of the mark-space type wherein the initiation and termination of each mark signal is represented respectively by a pair of pulses and a single pulse of substantially constant duration; comprising a first, a second and a third capacitor, each of said capacitors having a charging circuit and a discharging circuit, said discharging circuits comprising a grid-controlled gaseous discharge tube for each of the respective capacitors coupled to a common discharging resistor, the discharging circuits of said first and said second capacitors having different time constants, means responsive to the initiation of said mark signal to close the charging circuits of said first and said second capacitors simultaneously to charge said first and said second capacitors, means comprising the respective grid-controlled gaseous discharge tube of said discharging circuits to discharge said first and said second capacitors in succession across said common discharging resistor, means responsive to the termination of said mark signal to close the charging circuit of said third capacitor to charge said third capacitor, means comprising the respective grid-controlled gaseous discharge tube to discharge said third capacitor across said common discharging resistor, and means to connect said discharging resistor to said transmitter.

16. Apparatus for keying a continuous wave transmitter for radio telegraphy transmission of the mark-space type wherein the initiation and termination of each mark signal is represented respectively by a pair of pulses and a single pulse of substantially constant duration, comprising a first, a second and a third capacitor, each of said capacitors having a charging circuit and a discharging circuit comprising a grid-controlled gaseous discharge tube, a coupling resistor and a discharging resistor, the discharging circuits of said first and said second capacitors having

different time constants, means responsive to the initiation of said mark signal to close the charging circuits of said first and said second capacitors simultaneously to charge said first and said second capacitors, means comprising the respective grid-controlled gaseous discharge tube of said discharging circuits to discharge said first and said second capacitors in succession across the discharging resistors of the respective discharging circuits, means responsive to the termination of said mark signal to close the charging circuit of said third capacitor to charge said third capacitor, means comprising the respective grid-controlled gaseous discharge tube to discharge said third capacitor across the discharging resistor of the respective discharge circuit, and means comprising said coupling resistors to couple said discharging resistors to said transmitter.

17. Apparatus for receiving continuous wave radio telegraphy signals of the mark-space type wherein the initiation and termination of each mark signal is represented respectively by a different number of pulses of substantially constant duration, comprising a first gaseous discharge tube having an input circuit and an output circuit, a second electron discharge tube having an input circuit coupled to the output circuit of said first electron discharge tube and an output circuit coupled to the input circuit of said first electron discharge tube to render said second tube conducting when said first tube is non-conducting and conversely to render said second tube non-conducting when said first tube is conducting, a discharging circuit coupled to said first tube and being responsive only to the greater number of said pulses, means to apply said signals to the input circuit of said first tube, and means coupled to the output circuit of said second tube to reproduce said signals.

18. Apparatus for receiving continuous wave radio telegraphy signals of the mark-space type wherein the initiation and termination of each mark signal is represented respectively by a pair of pulses and a single pulse of substantially constant duration, comprising a first electron discharge tube having an input circuit and an output circuit, a second electron discharge tube having an input circuit coupled to the output circuit of said first electron discharge tube and an output circuit coupled to the input circuit of said first electron discharge tube to render said second tube conducting when said first tube is non-conducting and conversely to render said second tube non-conducting when said first tube is conducting, a discharging circuit coupled to said first tube and being responsive only to said pair of pulses, an integrating network coupled to the input circuit of said first tube, means to apply said signals to said integrating network, and means coupled to the output circuit of said second tube to reproduce said signals.

19. Apparatus for receiving continuous wave radio telegraphy signals of the mark-space type wherein the initiation and termination of each

mark signal is represented respectively by pairs of pulses and a single pulse of substantially constant duration, comprising a first electron discharge tube having an input circuit and an output circuit, a second electron discharge tube having an input circuit coupled to the output circuit of said first electron discharge tube and an output circuit coupled to the input circuit of said first electron discharge tube to render said second tube conducting when said first tube is non-conducting and conversely to render said second tube non-conducting when said first tube is conducting, a discharging circuit coupled to said first tube and being responsive only to said pairs of pulses, a pulse signal generator coupled to the input circuit of said first tube, means to apply said signals to said pulse signal generator, and means responsive to the output of said second tube to reproduce said signals.

20. Apparatus for receiving continuous wave radio telegraphy signals of the mark-space type wherein the initiation and termination of each mark signal is represented respectively by pairs of pulses and a single pulse of substantially constant duration, comprising a first electron discharge tube having an input circuit and an output circuit, a second electron discharge tube having an input circuit coupled to the output circuit of said first electron discharge tube and an output circuit coupled to the input circuit of said first electron discharge tube to render said second tube conducting when said first tube is non-conducting and conversely to render said second tube non-conducting when said first tube is conducting, a discharging circuit coupled to said first tube and being responsive only to said pairs of pulses, a pulse signal generator coupled to the input circuit of said first tube and being responsive only to signals having an amplitude above a predetermined threshold value, means to apply said signals to said pulse signal generator, and means responsive to the output of said second tube to reproduce said signals.
